HOOD FOR COPY-MAKING MACHINES

Kenneth R. Reick, 634 S. Main St., Lombard, Ill.

Filed Aug. 3, 1961, Ser. No. 66,186

Term of patent 14 years

(Cl. D61—1)

FIG. 1 is a perspective view of a hood for copy-making machines showing my new design wherein the front-to-rear plane of the hood is substantially flat;

FIG. 2 is a left-side elevational view thereof on an enlarged scale, the right side being a mirror image thereof;

FIG. 3 is a cross-sectional view thereof taken substantially on line 3—3 of FIG. 1;

FIG. 4 is a perspective view of a hood for copy-making machines showing a species of my new design wherein the front-to-rear plane of the hood is curved; and

FIG. 5 is a cross-sectional view thereof taken on substantially lines 5—5 of FIG. 4.

I claim:

The ornamental design for a hood for copy-making machines, substantially as shown and described.
